CAN OPENER AND SPOUT FORMER

Filed Nov. 4, 1931

UNITED STATES PATENT OFFICE

EMIL WISMAR, OF LOS ANGELES, CALIFORNIA

CAN OPENER AND SPOUT FORMER

Application filed November 4, 1931. Serial No. 572,975.

This invention relates to can openers, and has for an object to provide a can opener of unusually simple design, which is adapted not only to form an opening in a can, but also to provide a pouring spout in suitable position with respect to the opening to serve as a lip capable of assisting in pouring the liquid contents of the can through the opening.

10 The invention possesses other objects and advantageous features, some of which, with those enumerated, will be set forth in the following description of the invention's particular embodiment which is illustrated in 15 the drawing accompanying and forming a part of the specification.

Referring to the drawing:

Fig. 1 is a view in side elevation of a can opener embodying the principles of the present invention in proper position with respect to a can to be opened to start the opening process.

Fig. 2 is a view similar to Fig. 1, but showing the can opener in the position assumed thereby upon completion of the first step of the opening process.

Fig. 3 is another view similar to Fig. 1, but showing the can opener upon completion of the second step of the opening process.

Fig. 4 is an enlarged plan view of the top of the can after completion of the operation of the can opener. A portion of the figure is broken away to reduce its size.

35 Fig. 5 is a front elevation taken in the direction of the arrow 5 of Fig. 4.

Fig. 6 is a side elevation taken in the direction of the arrow 6 of Fig. 4.

40 Fig. 7 is a perspective view of the can opener.

The can opener of the present invention comprises preferably a flat strip 11 of suitable rigid material, preferably metal, at one end of which a prong 12 and a heel 13 are 45 formed. At the other end of the strip 11 an eye 14 is formed by bending the strip back upon itself in an open circle, thereby providing means for hanging the can opener upon a nail or hook, and also an abutment against which the operator may press

his hand without discomfort, with sufficient pressure to thrust the prong 12 through the top 16 of a can 17 to be opened.

The prong 12 and heel 13 are formed by cutting a slot or notch 18 in the end of the strip 11, this notch being preferably at a slight inclination with the side edges of the strip, so that the proximal edges 19 and 20 of the prong 12 and heel 13 incline from the associated end of the strip and toward the heel 13, as clearly shown upon Figs. 1 and 7. This inclination of the slot 18 also results in making the prong 12 wider at its base 21 than adjacent its outer end 22, and this outer end 22 is also provided with a point 23 to assist its penetration of the can to be opened.

Preferably the prong 12 and the heel 13 are of substantially the same length, and the notch 18 is of such width that the bead or crimping 26 which is usually provided at each end of that type of can which is commonly employed for fluids such as milk, may be received within the notch 18, with the prong 12 extending upon one side of the bead 26 after penetrating the top 16, and with the heel 13 extending outside the can and along the side wall 27.

The method which is employed when utilizing the can opener hereinabove described is substantially as follows: The can opener is held in the hand with the eye 14 resting against the palm of the hand and with the handle portion of the strip extending preferably between the first and second fingers. The point 23 of the prong 12 is then placed in contact with the top 16 of the can 17 to be opened, and closely adjacent the intersection of the top 16 with the side wall 27, substantially as illustrated upon Fig. 1. Sufficient pressure is then exerted upon the can opener to cause the prong 12 to penetrate the top 16. Because of the fact that the base 21 of the prong 12 is wider than the outer end 22 thereof, the opening 31 thus formed will be made longer as the prong 12 penetrates the top of the can, the result being that when the prong 12 has been thrust to the greatest possible distance through the top 16, the outer end 32 of the hole 31 will

be closely adjacent the inner surface of the side wall 27.

This movement of the can opener causes the heel 13 to extend outside the can and along the side wall, so that the lower end of the heel may be brought into engagement with the side wall below the bead 26 by swinging the upper end of the can opener laterally and radially outwards with respect to the can. After the heel has thus been brought into engagement with the outside surface of the side wall, the outward swinging movement of the can opener should be continued, causing the entire device to fulfil about the point of contact of the heel with the side wall. This moves the prong 12 laterally, drawing it toward the side wall until it engages the relatively thick portion thereof which is presented by the crimped edges of the top 16 and the side wall through which the prong will be unable to cut. Instead of cutting this relatively thick portion of the can, the prong will cause it to be drawn outwards, bending the adjacent portion of the side wall 27 outwards beyond the circle described by the edge of the top 16, thereby forming a lip 33, which is best shown upon Figs. 5 and 6.

This same movement of the can opener causes the lower end of the heel 13 to press inwards against the outer surface of the side wall 27, producing an indentation 34 (see Fig. 6), the result being that that portion of the lip 33 which lies between the bottom of the depression 34 and the outer extremity 36 or point of the lip, will be inclined from the vertical to a greater extent than would be the case if the indentation 34 were not formed.

40 Thus it may be seen that I have provided a novel means for opening a can and forming a pouring spot thereon, which is capable of operating in conjunction with the opening to assist in pouring the liquid contents from the can. Inasmuch as the lip inclines inwards and downwards from its outer extremity or point 36, there is less tendency for a drop or more of the liquid to adhere to the outer surface of the side wall 27 by capillary attraction, and this advantage is enhanced by the formation of the indentation 34, because this increases to a further extent the inclination of the lip from the vertical.

55 The can opener of the present invention is very easy to use, because of the fact that the prong 12 is relatively small, and therefore can be caused to penetrate the top of a can with relatively little effort. However, 60 since the prong is moved laterally after it is caused to penetrate the top, the opening 31 formed thereby is amply large to permit the liquid contents of the can to be poured therefrom.

65 It is to be understood that the details of

the invention as herein disclosed, are subject to alteration within the spirit or scope of the appended claims.

I claim:

1. A can opener comprising a flat rigid strip, and a prong and heel extending from an end of said strip substantially parallel to each other and of the same length, the proximal edges of said prong and heel being inclined from their outer ends and toward said heel, said prong having a point and being adapted to penetrate an end of a can and said heel being adapted to extend outside the can and along a side wall thereof as the prong penetrates the end of the can, said heel providing a fulcrum adapted to engage said side wall at a point spaced from said end and about which said strip may be swung to move said prong laterally, thereby elongating the hole formed by the prong and bending the adjacent portion of said side wall outwards in the form of a lip.

2. A can opener comprising a flat rigid strip, and a prong and heel extending from an end of said strip substantially parallel to each other and of the same length, said prong having a point and being adapted to penetrate an end of a can and said heel being adapted to extend outside the can and along a side wall thereof as the prong penetrates the end of the can, said heel providing a fulcrum adapted to engage said side wall at a point spaced from said end and about which said strip may be swung to move said prong laterally, thereby elongating the hole formed by the prong and bending the adjacent portion of said side wall outwards in the form of a lip.

In testimony whereof I have signed my name to this specification.

EMIL WISMAR.
